SPEED RESPONSIVE APPARATUS

Herbert L. Bone, Forest Hills, Pa., assignor to The Union Switch & Signal Company, Swissvale, Pa., a corporation of Pennsylvania

Original application May 17, 1935, Serial No. 22,029. Divided and this application April 2, 1937, Serial No. 134,633

8 Claims. (Cl. 175—355)

My invention relates to speed responsive apparatus.

An object of my invention is the provision of novel and improved speed responsive apparatus which is actuated by electrical means, and by which an unsafe indication due to loss of power or breakage of a part is avoided.

Speed responsive apparatus embodying my invention is particularly suitable for, although in no way limited to, use in connection with speed control systems for railway trains.

This application is a division of my copending application, Serial No. 22,029, filed May 17, 1935, now Patent No. 2,103,706, Dec. 28, 1937, for Speed responsive apparatus.

I will describe two forms of apparatus embodying my invention, and will then point out the novel features thereof in claims.

In the accompanying drawing, Fig. 1 is a diagrammatic view illustrating one form of apparatus embodying my invention, and Fig. 2 is a diagrammatic view of a modification of the apparatus of Fig. 1.

Similar reference characters refer to similar parts in each of the two views.

Speed responsive apparatus embodying my invention embraces a suitable speed responsive circuit interrupting means and a time limit electromagnetic means adapted to come into action a short period after the conditions actuating it have begun to exist. As shown in Fig. 1, the circuit interrupting means is a commutator, designated as a whole by the reference character C1, and the time limit electromagnetic means consists of two relays R1 and R2 of the direct current neutral type. The shaft 1 of the commutator C1 is operatively connected with a member the speed of whose movement it is desired to determine through the medium of any suitable drive mechanism such, for example, as a train of gears not shown. When the apparatus is utilized to control the circuits of a speed control system for railway trains, the shaft 1 is preferably operatively connected with an axle of the vehicle on which the apparatus is mounted, with the result that the speed of rotation of shaft 1 is in accordance with the speed of the railway train. A contact brush 2 is rigidly mounted on the shaft 1 for rotation therewith and is adapted to engage three annular segments 3, 4 and 5, the arrangement being such that the segment 3 is a complete ring and continuously engages the brush 2, but the segments 4 and 5 span only a little over 180° and alternately engage the brush 2. It follows that with the shaft 1 stationary,

electrical connection is continuously completed between the segment 3 and one or the other of the segments 4 or 5, depending upon the position of the contact brush 2, but that with the shaft 1 rotated, electrical connection is alternately completed between the segment 3 and the segments 4 and 5, the duration which the connection is completed in each case being dependent upon the speed of rotation of the shaft 1, and hence, in turn, dependent upon the speed of the driving member. It is to be understood, however, that my invention is not limited to any specific form of circuit interrupting means and the commutator C1 is shown for illustration only. It is clear that the commutator C1 may be constructed with the segments 3, 4 and 5 mounted rigid on the shaft 1 for rotation therewith, and the contact brush 2 held stationary should it seem desirable to do so.

The commutator C1 controls the energizing circuits for the relays R1 and R2, the arrangement being such that the circuits are alternately opened and closed with rotation of the shaft 1. The segment 3 is connected over wire 6 with one terminal of any convenient source of direct current such as a battery 7, and which battery is preferably of a predetermined given voltage. The other terminal of battery 7 is connected with one terminal of the operating winding of each of the relays R1 and R2 over wires 8 and 9, respectively. The second terminal of the operating winding of relay R1 is connected over wire 10 with the segment 5, and the second terminal of the operating winding of relay R2 is connected over wire 11 with the segment 4. Consequently, when brush 2 is in the position to engage the segment 4, current flows from the battery 7 over wire 6, segment 3, brush 2, segment 4, wire 11, operating winding of relay R2, and wire 8 back to the battery 7, and the relay R2 is energized, the potential difference across the terminals of the relay R2 being substantially the full voltage of the battery 7 since the ohmic resistances of wires 6, 8 and 11, and the contact resistance of brush 2 with segments 3 and 4 are negligible. When the brush 2 is moved around and engages the segment 5, current flows from the battery 7 over wire 6, segment 3, brush 2, segment 5, wire 10, operating winding of relay R1 and wire 9 back to the battery 7, and relay R1 is energized, the potential difference across the terminals of the relay R1 being substantially the full voltage of the battery 7 since the ohmic resistance of the circuit other than that of the operating winding of the relay is negligible. When the

brush 2 is rotated in response to rotation of shaft 1, the relays R1 and R2 are alternately supplied with current, the duration of each current impulse being in accordance with the speed of rotation of shaft 1. It is to be noted that at least one of the relays R1 and R2 is always supplied with current whatever the position of brush 2, since the segments 4 and 5 are made to slightly overlap, as explained hereinbefore. When the brush 2 is in a horizontal position, as viewed in Fig. 1, both relays are supplied with current in parallel.

The relays R1 and R2 are each provided with a circuit controlling armature in the usual manner, the armature 12 of relay R1 being adapted to be raised into engagement with a front contact 13 when the relay is energized, and to drop out of engagement therewith when the relay is deenergized. In like manner, the armature 14 of relay R2 is adapted to be raised into engagement with a front contact 15 when the relay is energized, and to drop away from engagement therewith when the relay is deenergized.

As set forth hereinbefore, the relays R1 and R2 constitute a time limit electromagnetic means adapted to come into action a short period after the conditions actuating it have begun to exist, and to this end, each relay R1 and R2 is provided with slow pick-up characteristics. That is to say, the armature 12 of relay R1, for example, is not raised into engagement with the front contact 13 until a predetermined time interval subsequent to initiating the energization of the relay by supplying current to its operating winding. Likewise, the armature 14 of relay R2 is not raised into engagement until a predetermined time interval subsequent to initiating energization of that relay by supplying current to its operating winding. In other words, the relays R1 and R2 each become effective to operate its respective armature a short period after current is initially supplied to the operating winding of the relay. The time delay in operating the armature is preferably the same for both relays R1 and R2. Such time delay in pick-up may be accomplished in any convenient manner, several arrangements being well-known in the art for providing a direct current relay with slow pick-up characteristics.

In addition to being provided with slow pick-up characteristics, the relays R1 and R2 are each provided with relatively high pick-up characteristics. For example, the relay R1 is so proportioned and adjusted that the tractive effort necessary to raise the armature 12 into engagement with the front contact 13 is produced when the value of a current flowing in its winding is, say, 75% of the ultimate current value resulting from a potential difference across the terminals of the relay equal to the full voltage of the battery 7. Likewise, the pick-up current of relay R2 is approximately 75% of the ultimate current effected when the full voltage of the battery 7 is impressed across the terminals of the relay. The relays R1 and R2 possess two constants—resistance and inductance. Due to inductance, the current resulting from a voltage impressed across the terminals of the operating winding does not at once rise to the value ultimately reached, that is, the value as indicated by Ohm's law. It follows that with the brush 2 stationary at the position illustrated in Fig. 1, the relay R2 is supplied with current the ultimate value of which is equal to that produced by the full voltage of the battery 7, as determined by the resistance of the relay, since the inductance delays the building up of

the current for a relatively short period only. Under this condition, the energization of the relay R2 is sufficient to attract the armature 14 and raise it into engagement with the front contact 15 at the expiration of the slow pick-up period. If the brush 2 is rotated at a speed such that the time interval the brush 2 makes engagement with the segment 4 during a half revolution is a little greater than the slow pick-up period of relay R2, the armature 14 is raised into engagement with contact 15 during this half revolution of the shaft 1 since the time constant resulting from inductance is less than the slow pick-up period and the ultimate value of the current as indicated by Ohm's law is effected for a sufficient length of time. During the half revolution the brush 2 breaks engagement with the segment 4, the energization of relay R2 dies away to substantially zero and the armature 14 is released. Hence, at such speed of shaft 1 the relay R2 is picked up and released once each revolution of the shaft 1. In the event the brush 2 is rotated at a speed such that the duration of the connection between the segments 3 and 4 by brush 2 is slightly less than the slow pick-up period of relay R2, the armature 14 remains down out of engagement with the contact 15. Under this condition of speed, the time interval between two successive impulses is sufficient for the energization of the relay to die away to substantially zero, notwithstanding the inductance causes a slight delay in the dying away of the current. Again, if the speed at which the brush 2 is rotated is relatively high, and rapid impulses of current are supplied to the winding of relay R2 and build up the magnetism in the magnetic circuit, the average value of the current flowing in the operating winding, however, does not reach the 75% pick-up value due to the inductance of the relay, and hence the armature 14 is not raised into engagement with contact 15 at such relatively high speeds. In other words, there is a critical speed above which the relay R2 is not picked up, and below which the relay is alternately picked up and released, while at zero speed the relay is steadily energized in case the brush 2 stops at a point where it makes engagement with the segment 4, and the relay is deenergized in case the brush 2 stops at a point where it is out of engagement with the segment 4.

Since the relay R1 is proportioned and adjusted similar to relay R2, the operation of the relay R1 in response to the different speed conditions of brush 2 is the same as just explained in connection with relay R2, except for the fact that the circuit for the relay R1 is governed during the opposite half revolution of brush 2. The speed of shaft 1 below which the relays R1 and R2 are picked up is hence determined by the pick-up time provided for the relays. For example, if it is desired to operate the relays R1 and R2 at speeds up to ten revolutions per minute of the shaft 1, that is, one revolution every six seconds, the pick-up time would be three seconds since each relay is energized during one-half of each revolution. Thus, at all speeds below ten revolutions per minute, each relay would be picked up while its circuit is closed by the brush 2, but that at all speeds above ten revolutions per minute both relays would remain down. At zero speed one or the other of the relays R1 or R2 would be picked up, and in the case the brush 2 should stop at the horizontal position, as viewed in Fig. 1, both relays would be picked up.

The relays R1 and R2 may be utilized to con-

trol indication and control devices to determine whether or not the driving member is moving at all, or is moving above or below a predetermined critical speed. As here shown, relays R1 and R2 5 govern an indication lamp 16 and a control magnet 18 by virtue of two simple circuits, both of which circuits include a battery 17 and one of which includes the contact 12—13 of relay R1, and the other of which includes the contact 10 14—15 of relay R2. Hence, the lamp 16 is steadily illuminated and the control magnet 18 is steadily energized when the speed of shaft 1 is zero, since at zero speed at least one of the relays R1 or R2 is steadily picked up. When the speed 15 of shaft 1 is not zero but is below the critical speed, and the relays are alternately picked up and released, the lamp 16 is flashed and the magnet 18 is intermittently supplied with current. When the speed is above the critical speed and 20 neither relay is picked up, the lamp 16 is dark and the magnet 18 is deenergized. As here shown, the magnet 18 is provided with slow-release characteristics, and hence is energized at zero speed and at speeds below the critical speed. 25 When the apparatus of Fig. 1 is used in connection with speed control systems for railway trains, the lamp 16 may be used to indicate to the operator of the train the zero and low speed conditions, and the magnet 18 may be used to effect 30 a control over the train brake equipment, and when so used an unsafe indication due to loss of power or breakage of a part is avoided.

If it were desired to have the critical speed of shaft 1 relatively low, additional segments may 35 be added to the commutator. In Fig. 2, the apparatus is the same as Fig. 1, except the commutator C2 is provided with four annular segments 19, 20, 21 and 22, and a second contact brush 40 23 is mounted rigid on the shaft 1. Each segment 19, 23, 21 and 22 spans approximately 46° with an adjacent space of approximately 44° between each two segments, and the brush 23 is positioned with respect to the brush 2 so that when one brush makes engagement with a segment the other brush is positioned at one of the insulating spaces. The battery 7 is connected 45 between the segment 3 of commutator C2 and one terminal of the operating winding of each of the relays R1 and R2 the same as in Fig. 1. The second terminal of the operating winding of relay R2 is connected with the segments 19 and 21 in parallel, and the second terminal of the operating winding of relay R1 is connected with the segments 20 and 22 in parallel, as will be readily 50 understood by an inspection of Fig. 2. Consequently, each relay R1 and R2 of Fig. 2 receives two current impulses each revolution of the shaft 1, and current is supplied to at least one of the two relays whatever the position of the contact 55 brushes 2 and 23. With the relays R1 and R2 proportioned and adjusted in the manner explained in connection with the apparatus of Fig. 1, a critical speed of 5 revolutions per minute of shaft 1 is provided since at such speed the 60 duration of a current impulse is substantially three seconds, inasmuch as each segment spans approximately one-eighth of a revolution and each impulse lasts for two segments due to the 65 position of the two brushes.

70 In Fig. 2, the control circuits for the indication lamp 16 and the control magnet 18 are governed by the relays R1 and R2 the same as in Fig. 1, and hence these devices are governed by the apparatus of Fig. 2 in response to rotation of the 75 shaft 1 in exactly the same manner explained in

connection with the apparatus of Fig. 1, except for the fact that the critical speed is relatively low.

Although I have herein shown and described only two forms of speed responsive apparatus embodying my invention, it is understood that various changes and modifications may be made therein within the scope of the appended claims without departing from the spirit and scope of my invention. 5

Having thus described my invention, what I claim is:

1. Speed responsive apparatus comprising a shaft adapted to be rotated at different speeds, a commutator including a pair of successive segments each of a predetermined length, a contact brush operatively connected with said shaft for rotation therewith and adapted to successively engage said segments, a first and a second relay each provided with slow pick-up characteristics, a current source; a control circuit for each relay including a winding of the relay, a particular one of said segments, said brush and the current source for successively and periodically energizing said relays with current impulses of a given 15 polarity in response to rotation of said shaft; an indicating device, and an operating circuit for energizing said device including a front contact of each of the two relays in parallel. 20

2. Speed responsive apparatus comprising a shaft adapted to be rotated at different speeds, a commutator including a pair of successive segments each of a predetermined length, a contact brush operatively connected with said shaft for rotation therewith and adapted to successively engage said segments, a first and a second relay each provided with slow pick-up characteristics, a current source; a control circuit for each relay including a winding of the relay, a particular one of said segments, said brush and the current 35 source for periodically energizing each of said relays with impulses of a current of like polarity in response to rotation of said shaft and the durations of which impulses are dependent upon the speed of the shaft; an indicating device, and an operating circuit for said device including a front contact of each of the two relays in parallel. 40

3. Speed responsive apparatus comprising a shaft adapted to be rotated, a commutator including a plurality of successive segments each of a predetermined length, contact brush means operatively connected with said shaft for rotation therewith and adapted to successively engage said segments with engagement made with the next preceding segment before the receding segment is disengaged, a first and a second relay each provided with slow pick-up characteristics, a current source; a control circuit for each relay including a winding of the relay, the current source, said contact brush means and alternate segments of the commutator for successively energizing each of said relays with impulses of current in response to rotation of the shaft and the durations of which impulses are dependent upon the speed of the shaft; an indicating device, and an operating circuit of said device including a front contact of each of the two relays in parallel. 50

4. Speed responsive apparatus comprising a member adapted to be actuated through an operating cycle at different speeds, circuit controlling contact mechanism operatively connected with said member and including a plurality of contacts which are successively closed once for each cycle and which contacts are each closed 60

75

during substantially equal portions of the cycle, said contacts made overlapping so that the preceding contact is closed before the receding contact is opened, a first and a second slow pick-up relay, a current source, a control circuit for each relay including a winding of the relay and alternate contacts of said mechanism as well as the current source, an indicating device, and an operating circuit for said device including a front contact of each of the two relays in parallel for energizing said device continuously when said member is stationary and deenergizing said device continuously when said member is actuated above a speed predetermined by the pick-up period of said relays.

5. Speed responsive apparatus comprising a member adapted to be actuated through an operating cycle at different speeds, circuit controlling contact mechanism operatively connected 20 with said member and including a plurality of contacts which are successively operated once for each cycle and which contacts are each closed during substantially equal portions of the cycle, said contacts overlapping so that the preceding 25 contact is closed before the receding contact is opened, a first and a second slow pick-up relay, a current source, an indicating device, an operating circuit for said device including a front contact of each of the two relays in parallel, and 30 a control circuit for each of said relays including a winding of the relay and alternating contacts of said mechanism as well as the current source to pick up at least one of said relays for intermittently displaying the indicating device when 35 said member is actuated at less than a speed predetermined by the pick-up period of the relays.

6. Speed responsive apparatus comprising a shaft adapted to be rotated at different speeds, a 40 commutator including two oppositely disposed and overlapping segments, a contact brush operatively connected with said shaft for rotation therewith and adapted to successively engage said segments, a first and a second slow pick-up relay, a slow release indicating device, an operating 45 circuit for said device including a front contact of each of said two relays in parallel, a current source, means to connect one terminal of said source to one terminal of the winding of each relay in parallel and to connect the other terminal of the source to said brush, and means to connect the segments to the other terminal of the 50 windings of said relays respectively to pick up at least one of the relays for actuating said indi-

cating device continuously only when the shaft is rotated at less than a speed predetermined by the pick-up period of the relays.

7. Speed responsive apparatus comprising a shaft adapted to be rotated at different speeds, a 5 commutator provided with four spaced segments of substantially equal lengths, two angularly disposed contact brushes fixed on said shaft for engaging said segments in response to rotation of said shaft with engagement with at least one 10 segment whatever the position of the shaft, a first and a second slow pick-up relay, a slow release indicating device, an operating circuit for said device including a front contact of each of said two relays in parallel, a current source, 15 means to connect one terminal of said source to one terminal of the winding of each relay in parallel and to connect the other terminal of the source to both of said brushes, means to connect the other terminal of the winding of the 20 first relay to a first and a third one of said segments in parallel and to connect the other terminal of the winding of the second relay to a second and a fourth one of the segments in parallel to pick up at least one of the relays for actuating 25 said indicating device continuously only when the shaft is rotated at less than a speed predetermined by the pick-up period of the relays.

8. Speed responsive apparatus comprising, a 30 member adapted to be actuated through an operating cycle at different speeds, circuit controlling contact mechanism operatively connected with said member and including a plurality of contacts which are successively closed once for 35 each cycle and which contacts are each closed during substantially equal portions of the cycle, said contacts made overlapping so that a preceding contact is closed before the receding contact is opened, a first and a second slow pick-up relay, a current source, a control circuit for each 40 relay including a winding of the relay and alternate contacts of said mechanism as well as the current source, an indicating lamp; and an operating circuit for said lamp including a front 45 contact of each of the two relays in parallel for illuminating said lamp continuously when said member is stationary, for flashing the lamp when said member is actuated at a speed below a predetermined speed and for causing the lamp to 50 remain dark when the member is actuated at a speed above said predetermined speed.

HERBERT L. BONE.
